W. B. TORANDO

RAILWAY CROSSING SIGNAL

Filed Aug. 17, 1922

UNITED STATES PATENT OFFICE.

WALTER B. TORANDO, OF DETROIT, MICHIGAN.

RAILWAY-CROSSING SIGNAL.

Application filed August 17, 1922. Serial No. 582,364.

To all whom it may concern:

Be it known that I, WALTER B. TORANDO, a citizen of the United States of America, residing at Detroit, in the county of Wayne and State of Michigan, have invented certain new and useful Improvements in Railway-Crossing Signals, of which the following is a specification, reference being had therein to the accompanying drawings.

10 This invention relates to a rail-way crossing signal of the warning type adapted to notify pedestrians and others of the approach of a train prior to the train reaching a crossing, such signals tending to reduce 15 accidents caused by pedestrians and others crossing tracks when the train is approaching.

My invention aims to provide a rail-way crossing with a tower, bridge or overhead 20 structure from which audible and visible signals may be operated to warn pedestrians of the approach of one or more trains, the audible signal being preferably in the form of a gong or bell and the visible signal in 25 the form of wig-wagging or oscillatory members or arms, which together with the tower, bridge or overhead structure may be illuminated at night and especially during the approach and passing of a train.

30 My invention further aims to provide rail-way crossing signals which are electrically operated and automatically controlled by a train or trains. The rolling stock is adapted to complete circuits setting 35 signals in operation before a train reaches a crossing and in this manner pedestrians or others will be warned in sufficient time to avoid an accident.

My invention further aims to accomplish 40 the above results by an exceedingly simple construction that will be hereinafter specifically described and then claimed and reference will now be had to the drawing, wherein

45 Figure 1 is a front elevation of the signal tower or bridge provided with the signals;

Fig. 2 is a side elevation of the same;

Fig. 3 is a plan of the signal tower or bridge, and

50 Fig. 4 is a diagrammatic view of the electrical wiring of my system of signalling.

In the drawing, the reference numerals 1 and 2 denote rails of parallel tracks at a crossing 3 and these rails constitute track

sections of considerable length, at each side 55 of the crossing 3, insulated, as at 4, from adjoining track sections and one of said tracks may be for eastbound traffic and the other for westbound traffic.

At one end of the crossing 3 is a tower, 60 bridge or overhead structure comprising posts or poles 5 connected by a cross member 6 suitably braced relative to the post 5, as at 7.

Mounted on the cross member 6 is an electric motor 8 and a train of reduction gears 9 which are adapted to be driven from the armature shaft 10 of the electric motor. The train of gears 9 includes a driven shaft 11 and mounted on the ends of said shaft are 70 cranks 12.

Pivotedly connected to opposite edges of the cross member 6, as at 13, are oscillatory members or arms 14 having the upper ends thereof pivotally connected, as at 16, to links 17 which in turn are pivotally connected to the outer ends of the cranks 12 so that said cranks may oscillate the members or arms 14. The lower ends of the members or arms terminate in signal members 18 that may 80 have configurations representing hands, as shown in Fig. 1 and incandescent lamps 19 can be mounted in the signal member.

Incandescent lamps 20 are also mounted on the posts 5 and the cross member 6, and 85 an audible signal, as an electric bell 21, is also mounted on the cross member.

In order that the electric motor and visible and audible signals may be placed in 90 operation a suitable source of electrical energy, as battery cells 22 and 23 may be employed and these battery cells, together with an electro magnet 24 and switches 25 and 26 may be located on the cross member 6, at 95 the base of one of the posts 5, or at any suitable location where electrical connections can be safely and conveniently established, in connection with the rails 1 and 2 of each track. The switch 26 is employed to render the motor 8 and mechanism driven thereby temporarily inoperative during repair.

100 Considering the electrical connections for one of the tracks, the rail 1 is connected by wires 27 and 28 to the battery cells 22 and said battery cells by wire 29 to the electro-magnet 24, which in turn is connected by a wire 30 to the rail 2. Rolling stock connecting the rails 1 and 2 closes the electro-

magnet circuit and with the switch 25 in position to be actuated by the energized electro-magnet 24, said switch completes a motor circuit which is as follows:

- 5 From battery cells 23 by wire 31 to the electric bell 21 and then by wire 32 to the switch 26 or the incandescent lamps 19 and 20. From the switch 26 by wire 33 to the motor 8 and then by a wire 34 to a contact 35
 10 of the switch 25, said switch being connected by a wire 36 to the battery cells 23.
- Immediately upon an engine or car truck passing onto the insulated section of the track, the wheels and axle close the electro-magnet circuit and causes the switch 25 to close the motor circuit, thus placing the motor in operation to wigwag or swing the signal members 18. The audible signal is placed in operation and the incandescent
 15 lamps illuminated at night, and all of this takes place while the train is on the insulated section of track. The other track has a normally open circuit with the electro-magnet circuit so that a train on said track may place the signals in operation, such circuit being maintained by wires 37 and 38.
- 20 It is obvious that the motor 8 and the train of gears 9 may be enclosed by a suitable housing on the cross member 6; that a light
 25 duty motor may be used; that the overhead structure may be of sufficient height to permit of the signals being observed over the top of a train; that suitable insulation and connections will be used and where the incandescent lamps are placed and that the

signal apparatus is applicable for various kinds of crossings and railways.

While in the drawing there is illustrated a preferred embodiment of my invention, it is to be understood that the structural elements are susceptible to such changes, in size, shape and manner of assembling, as fall within the scope of the appended claim.

What I claim is:—

45 In a railway crossing signal, the combination of insulated track sections at a crossing, an overhead structure adjacent said track sections, oscillatory arms pivotally mounted on opposite sides of said overhead structure, an electric motor adjacent one of said arms, 50 a train of gears driven by said motor, a shaft driven by said train of gears and having cranks at the sides of said overhead structure, links connecting the cranks of said shaft to the upper ends of said arms and adapted to oscillate said arms, an electrical circuit for said motor, visible and audible signals on the overhead structure and in said motor circuit, a track circuit including a suitable source of electrical energy, and an 55 electro magnet switch controlled by the track circuit and adapted to complete the motor circuit when rolling stock is on said insulated track sections.

60 In testimony whereof I affix my signature in presence of two witnesses.

WALTER B. TORANDO.
